UNITED STATES PATENT OFFICE.

ARTHUR R. SMITH, OF SCHENECTADY, NEW YORK.

FLOORING AND THE LIKE.

Application filed June 11, 1928. Serial No. 284,299.

The present invention relates to the laying of boards, such as floors, and while it is not limited thereto necessarily, it finds particular utility in connection with hard-wood floors.

The object of my invention is to provide an improved construction of board, such as floor board, and an improved means for fastening the same in place, and for a consideration of what I believe to be novel and my invention, attention is directed to the accompanying description and the claims appended thereto.

In the drawing, Fig. 1 is a perspective view of a portion of a floor embodying my invention; Fig. 2 is a sectional view through several of the boards shown in Fig. 1; Fig. 3 is a perspective view on a larger scale of a fastener which forms a part of my invention, and Fig. 4 is a perspective view of another form of fastener.

Referring to the drawing, 5 indicates a sub-flooring supported by floor joists 6 and upon which flooring embodying my invention is shown as being laid.

According to my invention, I provide floor boards 7 having narrow grooves 8 along each edge, and for fastening the boards in place, I provide metal fasteners or grips having portions which fit into the grooves and especially arranged openings through which the nails are driven. The fasteners illustrated in Figs. 1, 2 and 3 are shown as being formed from sheet metal which is reversely bent on itself to provide a top wall 9, side flanges or tongues 10 and spaced, downwardly-projecting supports or feet 11. At its central portion, top wall 9 is provided with a depression 12 for the reception of the nail head. At the center of the depression is a nail hole 13 and in each of the downwardly-projecting supports or feet is a nail hole 14. Nail holes 14 are oblong to permit a nail to extend through them at an angle and they are positioned to direct the nail at the desired angle. On their undersides at the ends, flanges 10 are preferably provided with downwardly-projecting knife edges or sharpened extensions 15 which when the flanges 10 are forced into the grooves 8 bite into the wood to hold the boards against endwise movement. I may, if desired, make the folds which form flanges 10 so they do not quite touch each other, thus giving a little spring action to take up clearance in the groove.

Beneath grooves 8, the boards are cut away at an angle as is indicated at 16, the angle being at least as great as that at which the nails extend when passed through the holes in the fasteners. With this arrangement, the nails are not driven through the boards. This is an important consideration, especially in connection with hard-wood flooring for it is difficult to drive nails through hard-wood and in some cases it is necessary to drill holes in the boards for the nails, a thing which is an expensive operation and adds greatly to the cost of laying the floor. Also, when nails are driven in the boards, especially adjacent to the ends of the boards, it happens often that the tongue splits which makes it difficult if not impossible to draw the boards together properly and sometimes requires the replacing of the split board. By my invention, these difficulties are avoided entirely.

In the vicinity of grooves 8 and below them, the boards are cut back as is indicated at 17 to provide space between the boards for the fasteners. There remain engaging edges on the boards which are indicated at 18.

In laying the flooring, the first board is put in position and anchored at suitable intervals by the fasteners, the nails, indicated at 19, being driven through the openings in the fasteners into the sub-flooring as is clearly shown in Fig. 2. The individual fasteners may be of a length of the order of one or two inches and may be placed apart a distance of the order of two feet although in any particular case they may be further apart or closer together as is found desirable. The flanges 10 of the fasteners fit nicely in grooves 8, the down-turned knife edges 15 biting into the wood, as already pointed out, to hold the board from movement edgewise. Feet 11 engage the sub-flooring and serve to hold the fasteners straight and to keep them from being bent downward either accidentally or when the nails are being driven. The provisions of a means, such as the feet 11, for supporting the fasteners from the sub-flooring so as to positively position them is one important feature of my construction for by this means the fasteners are all held straight so that when the next board is put in position no difficulty is experienced in fitting its grooves onto the outwardly-projecting flanges of the fasteners.

After the first board is in position, others are positioned relatively to it in the usual manner for laying floors, the groove in the edge of each board being driven over the 5 projecting flanges of the fasteners of the preceding board, and the boards being drawn together by driving the nails at an angle as is well understood. Since the boards are alike on both edges, there being no tongue 10 edge, it will be seen that there is no right and left hand to a board. This means that in laying a floor with boards embodying my invention there will be less waste in matching grain, in cutting mitred joints 15 and in ripping boards. This results also in a saving in labor.

A further advantage of my invention is that in laying a floor, the floor may be started in the middle or at any point and laid in 20 both directions. This is of advantage in that it insures that both sides of the floor will be completed in a similar manner.

One of the troubles experienced with tongue and groove flooring is that a nail 25 driven through the tongue too close to the end of the board will split the tongue from the body, which results, frequently, in a loose end to the board. By my invention, this is avoided. The ends of the boards can be 30 firmly fastened down by fasteners located directly at the ends. Also, at abutted joints, a fastener may be located to bridge the joint or two fasteners may be located at the joint one on each side thus firmly holding down 35 the board ends and doing away with any necessity for putting a tongue and groove in the ends, a thing sometimes done in order to insure freedom from loose board ends.

The use of my invention results also in 40 the saving of a substantial amount of wood. The usual tongue and groove board is about one-third the thickness of the board, which leaves less than one-third for finishing and refinishing without reducing the upper side 45 of the groove to a dangerous thinness. By my invention the thickness of the tongue used becomes almost negligible so that the grooves may be made correspondingly narrower, thus providing a greater thickness of 50 board above the groove. If the upper section and the lower section of the board are left the same as a regular tongue and groove board, the thickness of the board may be reduced materially and still provide a board 55 equivalent to a regular tongue and groove board. For example, in the case of a 13/16 inch board, the thickness may be reduced to 5/8 inches. Also, a substantial saving results in the elimination of the usual tongue. 60 Floor boards are made narrow to reduce the shrinkage of individual boards so as to avoid cracks opening up in the laid floor. In the case of narrow flooring, the percentage of waste due to forming the tongue is large and 65 becomes a limiting factor in making narrow

boards. For example, in a two inch face board the waste due to the tongue is about sixteen per cent. By the elimination of the tongue and by making the board thinner after the manner pointed out above, I am 70 enabled to effect a total saving in lumber of the order of thirty per cent by the use of my invention.

The fasteners or grips may be made in various forms, either from sheet material 75 or as castings. In Fig. 4 I have shown a modification wherein the fastener is formed from a flat sheet suitably slotted and bent to provide the feet 20 and the flanges 21, leaving the top portion 22 having the central depression 23 in which the nail hole is formed. In feet 20 are the slots 24 for the nails. The ends are downturned and sharpened as is indicated at 25 to provide 80 edges corresponding to the edges 15 of Fig. 3. 85

In accordance with the provisions of the patent statutes, I have described the principle of operation of my invention, together with the apparatus which I now consider to represent the best embodiment thereof, but I desire to have it understood that the apparatus shown is only illustrative and that the invention may be carried out by other means.

What I claim as new and desire to secure 95 by Letters Patent of the United States, is:—

1. The combination with a board having a groove and a cut-away portion below the groove, of a fastener having a top wall which provides a flange which fits into the 100 groove and a supporting means for the flange, said top wall and supporting means being provided with openings to direct a nail in an angular direction, and said cut-away portion being at an angle such that a 105 nail extending at an angle through the openings does not pass through the material of the board.

2. The combination with adjacent boards having opposed edge grooves and cut-away 110 portions below the grooves, of fasteners between the boards having a top wall which provides flanges located in said grooves and supporting means for the flanges, said top wall and supporting means being provided 115 with openings to direct a nail in an angular direction, and nails which extend at an angle through said openings for anchoring the fasteners in position.

3. A fastener for use in anchoring a board to a supporting board, said fastener comprising a flange adapted to engage a groove in the first-named board and transversely spaced supporting feet adapted to engage 120 said supporting board.

4. A fastener for use in anchoring a board to a supporting board, said fastener comprising a top wall which provides a flange adapted to engage a groove in the first-named board and a supporting foot adapted 125 130

to engage said supporting board, said top wall and foot being provided with holes for directing a nail at an angle into the supporting board.

5. A fastener for the purpose stated, comprising a top wall, flanges projecting from each side of the top wall, and supporting feet depending from the top wall, said top wall and feet being provided with openings 10 for directing a nail.

6. A fastener for the purpose stated, comprising a top wall, flanges projecting from each side of the top wall, and supporting means depending from the top wall, said 15 top wall and supporting means being provided with openings for directing a nail.

7. A fastener comprising a top wall having a depression and an opening through the wall of the depression, flanges projecting 20 from the top wall, and supporting feet, said feet being provided with openings adapted to co-operate with the first-named opening for directing a nail.

8. A board having an undercut portion 25 along each edge below the face of the board, and a groove along each edge, whereby when two such boards are placed edge to edge there is provided a space beneath the face of the boards to receive a fastener, the lower 30 edge of the undercut portion extending at an angle such that a nail driven through a fastener will not pass through the material of the board.

9. A flooring comprising boards having

grooves in each edge and fasteners anchoring the boards in place, said fasteners comprising top walls having flanges which lie in said grooves and depending supporting feet, said top wall and feet being provided with openings which serve to direct a nail 40 angularly, and nails extending through said openings.

10. A fastener for use in anchoring a board to a supporting board, said fastener comprising a top wall which provides a 45 flange adapted to engage a groove in the first-named board and a supporting foot adapted to engage said supporting board, said top wall and foot being provided with holes for directing a nail at an angle into the 50 supporting board and said top wall being provided with an angularly extending sharpened edge.

11. The combination with a board having a groove and a cut away portion below the 55 groove, of a fastener having a flange which fits into the groove and a supporting foot for the flange, said cut away portion being at an angle such that a nail extending at an angle through the fastener does not pass 60 through the material of the board, and said flange being provided with an angularly extending edge which bites into the material of the board to hold the board against end-wise movement.

In witness whereof, I have hereunto set my hand this 9th day of June, 1928.

ARTHUR R. SMITH.
